UNITED STATES PATENT OFFICE.

LADURA ALEXANDER BROWN, OF UNIONTOWN, PENNSYLVANIA.

MULTIPLE-BREAK ELECTRIC SWITCH.

Application filed July 3, 1928. Serial No. 120,384.

This invention relates to electric switches, and more particularly to a multiple-break electric switch for making and breaking electric circuits under heavy load, and has for its object the provision of a switch of this class which will operate without producing a flame or flash.

The present switch is particularly adapted for use in coal mines and other places where a flash or flame would be liable to cause an explosion, since it operates entirely free of an arc.

In the drawings:

Figure 1 is a plan of a switch constructed in accordance with my invention, the top of the casing being broken away for clearness.

Figure 2 is a sectional elevation on the line II-II of Figure 1 and showing the switch in open position.

Figure 3 is a similar view to that of Figure 2, with the switch in closed position.

Figure 4 is a sectional end elevation of the switch.

Referring more particularly to the drawings, the numeral 2 designates the casing or box enclosure of the switch, which is preferably formed of metal for strength and for fire protection.

A plurality of posts 3 are secured to the base of the box 2 to support a plurality of square plates 4 formed of insulating material.

The plates 4 are arranged, one on top of the other, on the posts 3 and are locked into close contact by the nuts 5 threaded on the posts 3. The plates 4 have their abutting faces relieved to form circular recesses 6 adapted to receive circular plates 6^a also formed of insulating material.

The plates 6^a are mounted on the squared portion 7^a of a shaft 7, which is arranged centrally of the casing 2 and journaled in bearings 8 and 9. Suitable spacing washers or bushings 10 are mounted on the shaft 7 between the plates 6^a, and a nut 12 and bushing 13 are threaded on the shaft 7 at the top and bottom of the plates 6^a, respectively, to hold or lock the plates 6^a in position. The bushing 13 is locked on the shaft by a set-screw 14.

The shaft 7 is squared at its upper end to

receive a crank handle 15 for rotating the shaft when operating or closing the switch.

The plates 4 and 6^a are provided with openings 16 and 17, respectively, to receive contact members 18 and 19, adapted to be moved into and out of contact with each other when the plates 6^a are rotated.

The contact 16 in the lower plate 4 is connected to one of the posts 3 by a shunt lead 20, while the contact 16 in the upper plate 4 is connected to another of the posts 3 by a shunt lead 21. The posts 3, to which the leads 20 and 21 are connected, are each provided with line leads 22, so that the switch may be connected into one side of an electric circuit.

It will be readily understood from the above, that by simply rotating the handle 15, the plates 6^a may be rotated relative to the stationary plates 4 to move the contacts 19 into and out of contact with the contacts 18 to make and break the electric circuit, and that due to the novel mounting of the contacts 18 and 19 in the plates 4 and 6^a and the novel arrangement of the plates, there is substantially no air space between the plates, so that there is not sufficient air to support an arc-flame or flash when the contacts are disengaged. Also, due to the fact that the plates 4 and 6^a are formed of insulating material, the movable plates 6^a will cover the contacts 18, and the stationary plates 4 will cover the contacts 19 as the contacts are separated, thus covering the surfaces of the contacts and preventing them drawing an arc.

The upper end of the bushing 13 is flared outwardly to form a flange 25, and a lever 26 is secured to the flange 25 by bolts or screws 27. A coiled spring 28 has one end secured to an eye 29 mounted in the casing 2, and its other end secured to the free end of the lever 26, so that as the shaft 7 is rotated to move the plates 6^a into circuit closing position, the spring 28 will be tensioned.

A pawl 30 is pivoted on a pin 31 mounted in the bearing plate 8, and is adapted to be normally urged against the flange 25 by a spring 32, so that as the shaft 7 and bushing 13 are rotated, the pawl 30 will automatically enter a notch 33 in the flange 25.

and lock the switch in closed or circuit making position. A handle 34 is secured to the pawl 30 and projects upwardly through the casing 2, so that the pawl 30 may be disengaged from the notch 33 to release the shaft 7 and permit the spring 28 to reversely rotate the shaft 7 and move the plates 6* so as to open the switch.

A second pawl 35 is pivoted on a pin 36 mounted in the bearing plate 8 and is adapted to be normally urged against the flange 25 by a spring 37, so that it will engage in a notch 38 in the flange 25 when the switch is in open circuit position. A handle 39 is secured to the pawl 35 and projects upwardly through the casing 2 so that the pawl 35 may be disengaged from the notch 38 to release the switch when it is desired to move it into closed position. It will be understood that the pawl 35 and its associated parts are not essential and may be omitted, if desired.

While I have shown my switch in its simplest form for the purpose of illustrating my invention, it will be understood that I do not wish to be limited thereto, since it may be readily modified by the addition of other series of contacts to the plates, or by successive groups of plates operable in unison, to control all the lines of a two-line, three or four-line circuit. It will also be understood that I do not wish to be limited to the specific details of construction since the locking pawls 30 and 35 may be mechanically or electrically controlled, and the plates may have a sliding rather than a rotary movement without departing from the scope of my invention as defined in the appended claims.

40 I claim:

1. A multiple-break electric switch, comprising a plurality of stationary plates formed of insulating material arranged parallel with and in contact with each other, said plates having their abutting faces relieved to form recesses, a plurality of movable plates formed of insulating material and mounted in said recesses, said movable plates being movable in a plane parallel with 45 said stationary plates, metallic contact members mounted in each of said plates and adapted to be engaged and disengaged by the movement of said movable plates, means for rotating said shaft and movable plates to engage said contact members, and a spring adapted to be tensioned when said shaft and movable plates are rotated to engage said contact members, said spring being adapted to reversely rotate said shaft and movable plates to disengage said contact members.

55 2. A multiple-break electric switch, comprising a casing, a plurality of stationary plates formed of insulating material mounted in said casing, said plates being arranged in parallel relation and in contact with each other, said plates having their abutting faces relieved to form recesses, a centrally arranged shaft journaled in said casing, a plurality of movable plates formed of insulating material mounted on said shaft and extending within said recesses, said movable

plates being adapted to be moved in a plane parallel with said stationary plates, metallic contact members mounted in each of said plates and adapted to be engaged and disengaged by the movement of said movable plates, and means for operating said shaft to move said plates.

3. A multiple-break electric switch, comprising a casing, a plurality of stationary plates formed of insulating material mounted in said casing, said plates being arranged in parallel relation and in contact with each other, said plates having their abutting faces relieved to form recesses, a centrally arranged shaft journaled in said casing, a plurality of movable plates formed of insulating material mounted on said shaft and extending within said recesses, said movable plates being adapted to be rotated in a plane parallel with said stationary plates, metallic contact members mounted in each of said plates and adapted to be engaged and disengaged by the movement of said movable plates, and means for rotating said shaft and movable plates.

4. A multiple-break electric switch, comprising a casing, a plurality of stationary plates formed of insulating material mounted in said casing, said plates being arranged in parallel relation and in contact with each other, said plates having their abutting faces relieved to form recesses, a centrally arranged shaft journaled in said casing, a plurality of movable plates formed of insulating material mounted on said shaft and extending within said recesses, said movable plates being adapted to be rotated in a plane parallel with said stationary plates, metallic contact members mounted in each of said plates and adapted to be engaged and disengaged by the movement of said movable plates, and means for rotating said shaft and movable plates.

5. A multiple-break electric switch, comprising a casing, a plurality of stationary posts secured to said casing, a plurality of stationary plates formed of insulating material mounted in said casing and secured on said posts, said plates being arranged in parallel relation and in contact with each other, said plates having their abutting faces relieved to form recesses, a centrally arranged shaft journaled in said casing, a plurality of movable plates formed of insulating material mounted on said shaft and extending within said recesses, said movable plates being adapted to be rotated in a plane parallel with said stationary plates, metallic contact members mounted in each of said

plates and adapted to be engaged and disengaged by the movement of said movable plates, means for rotating said shaft and movable plates in one direction to engage

5 said contact members, and a spring adapted to be tensioned when said shaft and movable plates are rotated to engage said contact

members, said spring being adapted to rotate said shaft and movable plates in the reverse direction.

10 In testimony whereof, I have hereunto signed my name.

LADURA ALEXANDER BROWN.
